UNITED STATES PATENT OFFICE.

LOUIS P. LAWRENCE, OF PASSAIC, NEW JERSEY, ASSIGNOR TO THE LAWRENCE RAILWAY BRAKE COMPANY, OF NEW YORK, N. Y.

BRAKE SADDLE AND SHOE.

SPECIFICATION forming part of Letters Patent No. 372,810, dated November 8, 1887.

Application filed August 15, 1887. Serial No. 246,960. (No model.)

To all whom it may concern:

Be it known that I, LOUIS P. LAWRENCE, of Passaic, in the county of Passaic, State of New Jersey, have invented certain new and useful Improvements in Brake Saddles and Shoes, of which the following is a specification.

This invention relates to certain improvements in brake saddles and shoes, and especially to devices for uniting the saddles and 10 shoes.

The object of my invention is to unite the brake saddles and shoes in such a manner that they can be connected or disconnected very easily and rapidly, and the shoes are held securely on the saddles, and there is no danger of the shoes dropping off when they become worn off.

The invention consists in the combination, with a brake-saddle and a side-flanged brake-shoe, of a bolt passed transversely through apertures in the saddle and shoe and provided at one end with a pivoted key.

The invention also consists in the construction and combination of parts and details, as 25 will be fully described and set forth herein-after, and then pointed out in the claims.

In the accompanying drawings, Figure 1 is a face view of the inner side of my improved brake saddle and shoe. Fig. 2 is an outer 30 edge view of the same. Fig. 3 is a longitudinal sectional elevation of the same on the line $x-x$, Fig. 2. Fig. 4 is a horizontal sectional view of the same on the line $y-y$, Fig. 2.

Similar letters of reference indicate corresponding parts.

The brake-saddle A is provided with the side flanges, B, which at or near the middle of their length are united by U-shaped walls forming the box C, for receiving a lever or the 40 brake-beam, and on which the said saddle is secured in any well-known manner. The brake-shoe D, which is shaped to fit snugly against the curved side of the saddle, is provided with the flanges E, which can 45 brace the flanges of the saddle, the latter being of such size that it can be placed into the shoe.

A square or rectangular bolt, F, is used to

fasten the shoe on the saddle, said bolt being passed transversely through apertures $a-a'$ in 50 flanges E of the shoe and the aperture of the saddle, said aperture in the saddle being formed between the inner side of the box C and the inner surface of the curved part of the saddle.

The bolt F has a square or rectangular head, G, and to receive said head the aperture a in that flange of the shoe facing the flange of the wheel is made of sufficient size that the outer end of said head is flush with the outer side of 60 said flange and cannot come in contact with the flange of the wheel. At the opposite end the bolt is forked, and between the shanks of said fork the key H is pivoted, which, when the bolt is passed through the apertures in the 65 saddle and shoe, hangs vertically and prevents the bolt passing out of the apertures in the saddle and shoe, and thus prevents accidental separating of the saddle and shoe, and also prevents the shoe from dropping off the 70 saddle when the wearing-surface of the said shoe has been worn off entirely. When the shoes are secured on the saddle by means of bolts passed through the wearing-surface of the shoe and the corresponding surface of the 75 saddle, the heads of the bolts are worn off with the shoe, and when said heads are worn off entirely the shoes drop off.

When it is desired to disconnect my improved shoe and saddle, the key H is swung 80 up to be in line with the bolt, when the latter can easily be withdrawn.

Having thus described my invention, I claim as new and desire to secure by Letters Patent—

1. The combination, with a brake-saddle and a side-flanged brake-shoe embracing the saddle, of a bolt passed transversely through apertures in the saddle and flanges of the shoe and a pivoted key on one end of said bolt, substantially as herein shown and described. 85
2. The combination, with a brake-saddle and side-flanged brake-shoe, of a bolt passed transversely through apertures in the saddle and the flanges of the shoe, said bolt being provided at one end with a rectangular head and 90 at the opposite end with a pivoted key, the 95

flange of the brake-shoe facing the wheel-flange being provided with an opening of sufficient size to receive the entire bolt-head, so that the outer surface of said head will be flush 5 with the outer surface of said flange, substantially as herein shown and described.

In testimony that I claim the foregoing as my

invention I have signed my name in presence of two subscribing witnesses.

LOUIS P. LAWRENCE.
